INVENTOR
A.C. McGUGIN

ATTORNEY

UNITED STATES PATENT OFFICE.

ALBERT C. McGUGIN, OF DENVER, COLORADO.

DESIGN FOR A RUG.

53,925.

Specification for Design.

Patented Oct. 7, 1919.

Application filed May 9, 1919. Serial No. 296,006. Term of patent 14 years.

To all whom it may concern:

Be it known that I, ALBERT C. McGUGIN, a citizen of the United States, residing at Denver, in the county of Denver and State of Colorado, have invented a new, original, and ornamental Design for Rugs, of which the following is a specification, reference being had to the accompanying drawing, forming part thereof.

The figure is a plan view of a rug showing my new design.

I claim:

The ornamental design for a rug, as shown.

ALBERT C. McGUGIN.
